Primary Examiner — Mitchell Siegel*(74) Attorney, Agent, or Firm* — Paul M. Thompson; Cochran Freund & Young LLC(57) **CLAIM**

The ornamental design for a sports training device, as shown and described.

DESCRIPTION

FIG. 1 is an isometric view of a sports training device showing my new design.

FIG. 2 is a top plan view thereof.

FIG. 3 is a bottom plan view thereof.

FIG. 4 is a right side elevation view thereof.

FIG. 5 is a left side elevation view thereof.

FIG. 6 is a rear elevation view thereof.

FIG. 7 is a front elevation view thereof; and,

FIG. 8 is an isometric view thereof showing an environment in which a sports training device may be used.

The broken line showing is included for the purpose of illustrating and forms no part of the claimed design.
